UNITED STATES PATENT OFFICE.

BENGT M. W. HANSON, OF HARTFORD, CONNECTICUT; BIRNAR A. HANSON AND CLARENCE E. WHITNEY EXECUTORS OF SAID BENGT M. W. HANSON, DECEASED.

TESTING OR MEASURING APPARATUS.

Application filed July 9, 1923. Serial No. 650,292.

This invention relates to devices for testing or measuring the dimensions, spacing, trueness, etc., of various kinds of members or parts, and has particular reference to apparatus of the type disclosed in my co-pending application Serial No. 640,348, filed May 21, 1923.

An aim of the invention is to provide an apparatus of this sort having various features of novelty and advantage.

A particular aim of the invention is to provide certain improvements in an apparatus of this sort by means of which the instrumentalities may be quickly and readily adjusted one relative to the other, thus increasing the efficiency of the apparatus.

Other objects will be in part obvious and in part pointed out hereinafter.

The invention accordingly consists in the features of construction, combination of elements and arrangement of parts which will be exemplified in the construction illustrated in the accompanying drawings wherein is disclosed one embodiment which the invention may take.

In these drawings:

Figure 1 is a diagrammatic view showing the complete apparatus in side elevation, parts being in section;

Fig. 2 is a front elevation of the apparatus, certain parts being broken away for purposes of clearness; and

Fig. 3 is a sectional view taken substantially on line 3—3 of Fig. 2.

Fig. 4 is a sectional view in side elevation of the indicating device, this view being taken substantially on line 4—4 of Fig. 2;

Fig. 5 is a detail view showing one of the V rests and a knife edge associated therewith.

Referring to the drawings in detail, and particularly to the diagrammatic showing of Fig. 1, *a* indicates a suitable base on the longitudinal ways *b* of which is mounted for adjustable movement, means for supporting the piece to be tested as, for instance, head and tail stocks, one of which is designated by the letter *c*. These respective stocks may have centers *d* and *e*, shown in Fig. 2. Also, mounted on the base for adjustment in parallelism with the way *b* is a fulcrum member or rest *f* on the top of which is fulcrumed, by means of knife edges *g*, a swinging support or arm *h* carrying on

its forward end a longitudinally extending head or bracket *i* provided with ways *k* in which an indicator slide *l* is mounted. Secured to this slide is an indicator mechanism which includes a point *n* adapted for engagement with the piece to be tested, an indicating finger *o*, and a connection between the point and finger through which a slight movement of the point causes a relatively large movement of the finger. This connection may include a point lever 10 carrying at its lower end the point *n* and fulcrumed adjacent its lower end in a V rest 11; a link lever 12, and a magnifying lever 13, the latter being fulcrumed as at 14, and the opposite ends of the link lever being pivotally associated with the point lever and the magnifying lever by means of the knife edges 15 and 16. The magnifying lever is in the form of an inverted U straddling the right hand end of the lever 12. Secured to the lower end of this magnifying lever is a weight 100 which serves as a counterbalance in that it normally maintains the magnifying lever and the finger *o*, which is welded or otherwise secured to the weight, in vertical position. The V rests 17, in which the knife edges 14 engage, are fixed, being carried, in the present instance, by the back plate 18 of the casing 19 which houses the indicator. The parts of the indicator are maintained in cooperative relation by the spring 20. For the purpose of accurately indicating the proper positioning of the indicator relative to the piece of work being tested, suitable mechanism is provided which may take the form of the drop pin arrangement designated generally by the letter *p*. This drop pin arrangement includes a plunger 30 mounted for sliding movement in a bracket 31 secured to the left hand end of the head or slide bracket *i*. Fixed to the plunger 30 is a collar 32 behind which is a spring 33 so that the plunger is normally urged towards the right, referring to Figs. 2 and 3. Carried by the collar 32 and a portion of the bracket 31 are a pair of aligned studs 34 and 35 between which the drop pin 36 is adapted to be positioned. Rough adjustment of the slide *l*, together with the parts carried thereby, may be effected by turning a knob *g* directly mounted on the screw *r* associated with the slide *l*, and fine adjustment is effected by turning the knob *s*, which may be connected

to the screw *r*, through the intermeshing pinion *t* and gear *u*. In Fig. 2, the pinion and gear are shown out of mesh. To bring them into mesh, the knob *s* is pulled out. Disposed opposite to the operative end of the plunger 30 of the drop pin arrangement, and carried by, in the present instance, the housing 19 is an anvil 40 between which and the plunger suitable gauge blocks may be selectively interposed. These gauge blocks may rest on the surface 41, one of the gauge blocks being shown in the drawings and indicated by the numeral 42. In accordance with the present invention, I provide the apparatus with means for designating when the indicator has been adjusted within a relatively small limit to its proper position, the advantage of this being that considerable time may be saved in adjusting the indicator in that the indicator may be quickly moved almost to its final position and when this point is reached, the operator will be notified that such is the case, and only thereafter is it necessary for the operator to slowly adjust the indicator. Since, in the present instance, the drop pin arrangement is provided for indicating the proper positioning of the indicator, my improved means for signalling or designating when the indicator has been almost brought to its final position is associated with the drop pin arrangement. In the present instance, this designating or signal device includes a pin 50 extending through and slidably mounted in the anvil 40, and a designating lever 51 the short end of which is acted upon by movement of the pin 50. The pin 50 normally extends beyond the face of the anvil but a very slight extent, say one one-thousandth of an inch. The pin 50 has a head 52 against which engages a knife edge 53 on the lower end of the lever 51. The lever 51 is pivoted or fulcrumed by means of a knife edge as at 54. The upper end of the lever 51 is adapted to move over a scale 55. It will be noted that the vertical distance between the point of engagement of the lever 51 against the pin 50 and the fulcrum point 54 is extremely small as compared with the long end of the lever so a very minute movement of the pin 50 will be registered by a relatively large movement of the long end of the lever over the scale 55. The lever is held in operative position by a spring 56.

The operation of the apparatus is briefly as follows. The piece to be tested, such as the screw threaded member *w*, is placed between the centers *d* and *e*, and the fulcrum rest *f*, together with the parts carried thereby, is adjusted so that the point *n* may be brought into engagement with the work. The drop pin 36 is positioned between the studs 34 and 35 so that it is horizontally disposed as shown in the drawings, and then

the slide *l*, together with the indicator carried thereby, is quickly or roughly adjusted relative to the drop pin arrangement by turning the knob *q*. Assuming that the gauge block 42 is not used in the first instance, when the indicator has been brought almost to its final position, the protruding end of the pin 50 will engage the plunger 30, causing the pin to move to the right and thereby swing the designating lever 51. The operator, upon observing movement of the designating lever 51, will know that the indicator has been brought approximately, that is to an extremely small limit, to its proper position. Then the knob *s* is pulled out to intermesh the gears *t* and *u*, and the knob *s* is slowly turned bringing the anvil against the end of the plunger 41, and when this engagement takes place, the drop pin will start to fall indicating that the indicator has been brought to the proper position. The forward end of the swinging arm *h* is then lowered to bring the point *n* into engagement with the work, and the work is longitudinally adjusted to a position where the point equally engages both sides of the thread groove at which time the indicator finger *o* will stand at zero. Then the indicator is raised, the drop pin is reset, a gauge block 42 corresponding to the lead of the thread to be tested is positioned as shown in Figs. 2 and 3, the indicator is quickly moved by the knob *q* until the signal device, owing to the engagement of the protruding end of the pin 50 against the gauge block 42, signifies to the operator that the anvil is in close proximity to the gauge block, and then the indicator is slowly moved by turning the knob *s* until the anvil is in engagement with the gauge block, this engagement being designated by the falling movement of the drop pin 36. The point *n* is then engaged in one of the successive convolutions of the screw thread, and if the lead of this thread is not absolutely correct, the free end of the indicating finger *o* will stand to one or the other side of the zero mark of the scale *o'* and thus register the extent of inaccuracy in the lead. It is, of course, understood that with the arrangement described a slight movement of the point *n* is magnified many times in the finger *o* so that the extent of inaccuracies in the lead may be determined with the utmost precision. It will also be seen that a relatively slight movement of the pin 50 will be registered as a relatively large movement by the free end of the designating lever 51 so that the operator will be instantly apprised of the movement of the pin 50 against the plunger 41 or the gauge block 42, as the case may be. Thus, the operator may quickly bring the indicator into close proximity to its proper position relative to the drop pin arrangement and then, by turning the knob *s* slowly advance

the indicator towards the drop pin arrangement and, by observing the extent of movement of the designating lever 51 over the scale 55, this final setting may be brought 5 about with a saving of time.

The V rests for the several knife edges are of a novel construction. These V rests are similar in arrangement so that it is sufficient to describe but one of them, for 10 instance the rest 11 for one knife edge. This V rest includes a pair of blocks 60 and 61 positioned in a recess 62 in a part or support 63 and may be held in this recess by the screws 64. The two blocks have abutting 15 plane surfaces 65 and the corresponding corners of the blocks, where these blocks meet, are bevelled as at 66 so as to form a symmetrical V. The reason for this arrangement is that from a practical stand-point 20 it is very difficult, to say the least, to cut in a solid block a V, the corner or angle of which is accurate and sharp. With the present arrangement, however, the V rest may be made with extreme accuracy at a 25 greatly reduced cost. After the sides of the blocks 60 and 61 have been properly faced, they may be positioned side by side in accurate alinement, and then the corresponding corners of the blocks may be bevelled 30 off with the assurance that these two bevelled faces are at the same angle. The blocks are then positioned in a recess 62, as shown most clearly in Fig. 5, and, obviously, 35 where the bevelled faces meet is a sharp, accurate corner which receives the knife edge.

As previously stated, the showing in the present instance is by way of illustration only. It is, of course, obvious that the apparatus 40 may be employed for testing other than screw threaded members and the parts may be variously arranged.

I claim as my invention:

1. In an apparatus of the character described, 45 an indicating device, means having a definite relation to the apparatus for supporting a piece to be tested, means for indicating the positioning of said indicator relative to the piece to be tested, means for adjusting said indicator relative to said position indicating means, and means for designating when said indicator has been brought into the approximate desired position relative to the piece to be tested.

2. In an apparatus of the character described, 50 an indicator including a point and an indicating finger associated therewith, means having a definite relation to the apparatus for supporting a piece to be tested, a drop pin arrangement for designating when said indicator has been brought into proper position relative to the work and including a pin adapted to be held by pressure in other than a vertical position and to be 55 turned by gravity when the pressure is re-

lieved, means for adjusting said indicator relative to said arrangement, and means for designating when said indicator has been brought into close proximity to the proper position relative to said drop pin arrangement. 70

3. In an apparatus of the character described, 75 an indicator including a point and an indicating finger associated therewith, means having a definite relation to the apparatus for supporting a piece to be tested, a drop pin arrangement for designating when said indicator has been brought into proper relation to the piece to be tested and including a pin adapted to be held by pressure 80 in other than a vertical position and to drop when the pressure is relieved, means for adjusting said indicator relative to said arrangement, and means adapted to cooperate with said drop pin arrangement and including a distance multiple arrangement for designating when said indicator has been adjusted into close proximity to the proper position relative to the drop pin arrangement. 85

4. In an apparatus of the character described, 90 an indicator, means having a definite relation to the apparatus for supporting a piece to be tested, a drop pin arrangement for designating when said indicator has been brought into proper relation to the piece to be tested and including a pin adapted to be held by pressure 95 in other than a vertical position and to drop when the pressure is relieved, means for adjusting said indicator relative to said drop pin arrangement, and means including a magnifying lever for designating when the indicator has been adjusted into close proximity to its proper position relative to said drop pin arrangement. 100

5. In an apparatus of the character described, 105 an indicator including a point and an indicating finger associated therewith, means having a definite relation to the apparatus for supporting a piece to be tested, means for indicating the proper positioning 110 of said indicator relative to the piece to be tested, means for adjusting said indicator relative to said first mentioned means, and means for designating when said indicator has been adjusted into close proximity to its proper position relative to the piece to be tested and including a member adapted to cooperate with said first mentioned means when the indicator has been brought into 115 close proximity thereto and a designating lever adapted to denote the extent of movement of said member. 120

6. In an apparatus of the character described, 125 an adjustable mounting, means having a definite relation to the apparatus for supporting a piece to be tested, an indicator mounted thereon including a point and an indicating finger associated therewith, a drop pin arrangement for designating when said indicator has been brought into proper 130

relation to the piece to be tested and including a pin adapted to be held by pressure in other than a vertical position and to drop when the pressure is relieved, a surface carried by said mounting and cooperatively positioned relative to said drop pin arrangement, means for adjusting said mounting relative to said drop pin arrangement, a pin located for sliding movement on said mounting and extending slightly beyond said surface, and a designating lever pivotally carried by said mounting and acted upon by movements of said pin.

7. In an apparatus of the character described, an adjustable mounting, means having a definite relation to the apparatus for supporting a piece to be tested, an indicator carried thereby and including a point and an indicating finger associated therewith, means for indicating the proper positioning of said mounting and the indicator carried thereby relative to the piece to be tested, means for adjusting said mounting relative to said position indicating means, and means for designating when said indicator has been brought into close proximity to the desired position relative to the piece to be tested, said last

mentioned means including a longitudinally movable pin carried by said mounting and adapted to engage said position indicating means slightly before the mounting engages the same and a lever pivoted in the mounting and having a relatively short end engaging said pin and a relatively long end denoting the extent of movement of the pin.

8. In an apparatus of the character described, an adjustable mounting, means having a definite relation to the apparatus for supporting a piece to be tested, an indicator carried thereby and including a point and an indicating finger associated therewith, means for indicating the proper positioning of said indicator relative to the piece to be tested, means for designating when said indicator has been brought into close proximity to the correct position relative to said position indicating means, a screw associated with said mounting for adjusting the same, means for rotating said screw at a relatively fast rate of speed to roughly adjust said indicator, and means associated with said screw for slowly rotating the same to effect a fine adjustment of said indicator.

BENGT M. W. HANSON.
